[57] **CLAIM**

The ornamental design for a bottle, as described and shown.

DESCRIPTION

FIG. 1 is a perspective view of a bottle embodying our new design;

FIG. 2 is a front elevational view of the bottle of FIG. 1, the side opposite being a mirror image thereof;

FIG. 3 is a top plan view of said bottle;

FIG. 4 is a side elevational view thereof;

FIG. 5 is a side elevational view opposite that of FIG. 4;

FIG. 6 is a bottom view thereof;

FIG. 7 is an enlarged, cross-section view of the bottle taken along lines 7—7 of FIG. 2; and,

FIG. 8 is an alternate embodiment of the view of FIG. 7, the other views of the second embodiment are the same as FIGS. 1 through 6 except that the raised vertical ribs on the right side of the bottle are grooves in the second embodiment.

The broken line showing of a bottle neck in FIGS. 1 through 5 is for illustrative purposes only and does not form part of the claimed design.
